Samuel Nundall
Letterz. Patent

The valuable referred to in these Letterz. Patent and
imprinting part of the same containing a description in the words
of Samuel Nundall himself of his improvement
in ~~the~~ ^{of} Reading, "See 2,"

Each syllable in a word distinguished as printed out
by one small mark (called a discriminated syllabication) placed
just below or above the face of the letters, and brim between the
last letter of one syllable and first letter of the next to that
which syllable in a word is, readily perceived by the reader
and the words pronounced with the same ease, when their
syllables are separated by spaces or hyphens, as in the
following words

Noting. Disposition. Headlong, were. Philosopher,
ical. Physiologically. Natural, of, phasis. —

The accented syllables are distinguished by double hyphens, that is, one above or below the right side of the last letter of the accented syllable as, Physiolog,
